LIGHTING FIXTURE

Thomas D. Phillips, Denver, Colo., assignor of
fifty per cent to Lillian Montaldo, New York,
N. Y.

Application October 31, 1938, Serial No. 237,804

2 Claims. (Cl. 240—78)

This invention relates to an interior lighting fixture and has for its principal object the provision of a fixture which will employ and distribute all of the light emitted from the modern fluorescent tubes.

Fluorescent tubes for lighting purposes are opaque, that is, light cannot pass through the tubes and if placed in the ordinary lighting fixture, they act to shadow or obstruct the light being reflected back from the rear of the tube. For this reason, the usual reflector or fixture is not efficient with fluorescent tube lighting.

The principal object of this invention is to provide a fixture which will utilize the light from all sides of each tube for efficient illumination and which will reflect, deflect and diffuse the light in directions which will uniformly illuminate a room from the ceiling to the floor.

Another object of the invention is to provide a lighting fixture in which fluorescent tubes of different colors may be used in the same fixture and if desired controlled independently so as to mix the colors to produce a light of any desired color for use in clothing fitting rooms, etc., where color matching is important.

A further object is to accomplish the above in a fixture which will be neat, ornamental and modernistic in appearance, easy to manufacture and install and easy to service after installation.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a perspective view of the improved fixture as it would appear in place.

Fig. 2 is a longitudinal section therethrough taken on the line 2—2, Fig. 1.

Fig. 3 is an enlarged cross section taken on the line 3—3, Fig. 2.

Fig. 4 is an enlarged detail section through one of the tube receptacles, taken on the line 4—4, Fig. 3.

The invention comprises a hollow elongated inverted canopy structure 10 adapted to be secured to the ceiling of a room by means of a fixture stud 11 extending from the usual conduit box fitting 12. All sides of the canopy 10

are curved inwardly and downwardly on a parabolic arc to a relatively sharp elongated apex.

A supporting bar 13 extends outwardly from each extremity of the apex of the canopy to support an open frame 14 corresponding in contour to the contour of the canopy 10. The frame 14 is formed with a lower stiffening flange 23. The end members of the frame 14 each carry a series of insulating tube terminal receptacles 15 for supporting the extremities of a parallel series 10 of fluorescent tubes 16. The receptacles 15 rest upon the flange 23. The terminals of the fluorescent tubes, indicated at 17, extend into the canopy 10 to a suitable tube transformer 18. The transformer in turn is connected to the regular lighting circuit as indicated at 19.

Any desired even number of tubes may be employed depending upon the brilliancy desired. An even number is desirable so that an equal number of tubes will be positioned on each side 20 of the canopy 10. As illustrated, four tubes are used, two on each side of the canopy.

Extending outwardly and downwardly from the flange 23 at each side of the frame are a series of hooked bracket members 20 which 25 support a sheet of translucent glass 21, such as frosted glass or white flash glass, below the tubes. The glass sheet 21 acts to diffuse and spread the light rays projected downwardly from the lower half of the tube 16 and the curved sides of the 30 canopy 10 act to project light rays from the upper half of the tubes at diffusing angles, as indicated at "A", so that the ceiling and side walls of the room will be lighted from the reflected light of the canopy.

It is preferred to have the tubes 16 of different colors, for instance, two of the tubes red and the remaining tubes green or blue so that when all tubes are on a mixture of light will be produced closely resembling white sun light. If 40 desired, each set of colored tubes may be controlled by a separate switch 24 so that either or both colors may be obtained as desired. These switches may be controlled by means of suitable pull chains 22.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A lighting fixture comprising: an elongated

canopy; curvated sides on said canopy extending inwardly and downwardly to an elongated apex; supporting members extending outwardly from said apex; an open frame supported by said supporting members below said canopy; a lower stiffening flange formed on said open frame; a series of tube terminal receptacles carried by the end members of said frame; a series of parallel, fluorescent tubes supported by their extremities in said receptacles; a series of hooked bracket members extending outwardly and downwardly from said frame; and an elongated glass plate supported by said latter members below said tubes.

2. A lighting fixture comprising: an elongated canopy; curvated sides on said canopy extending inwardly and downwardly to an elongated apex; supporting members extending outwardly from said apex; an open frame supported by said supporting member below said canopy; a series of parallel, equal-length fluorescent tubes in said frame; a horizontal, translucent glass plate; means for supporting said plate below said tubes, said tubes differing in color; means for controlling the tubes of different colors independently; and a fixture stud for securing said canopy to the ceiling of a room.

THOMAS D. PHILLIPS.
